UNITED STATES PATENT OFFICE.

THURE E. DAHL, OF NEW YORK, N. Y.

DESIGN FOR A BASE FOR LIGHTING FIXTURES.

Application filed July 21, 1921. Serial No. 486,574. Term of patent 3½ years.

To all whom it may concern:

Be it known that I, THURE E. DAHL, a subject of the King of Sweden, residing at New York, in the county of New York and State of New York, have invented a new, original, and ornamental Design for a Base for Lighting Fixtures, of which the following is a specification, reference being had to the accompanying drawing, forming part thereof.

Fig. 1 is a side view of a base for lighting fixtures, showing my new design.

Fig. 2 is a bottom plan view of the same, a part of the surface ornamentation being shown, it being apparent that the remaining portion is a repetition thereof.

I claim:

The ornamental design for a base for lighting fixtures, as shown.

THURE E. DAHL.
